(57) **CLAIM**

The ornamental design of a heat gun, as shown.

DESCRIPTION

FIG. 1 is a top view of a heat gun in accordance with the present invention;

FIG. 2 is a side view thereof;

FIG. 3 is a rear perspective view thereof;

FIG. 4 is a front and side perspective view; and,

FIG. 5 is a top perspective view thereof.

The broken lines in FIG. 1 depict a portion of the heat gun design which forms no part of the claimed design.

1 Claim, 5 Drawing Sheets
